UNITED STATES PATENT OFFICE

161,144

EYEBROW STENCIL

Ernest H. Westmore, North Hollywood, Calif.

Application September 19, 1949, Serial No. 5,066

Term of patent 14 years

(Cl. D86—10)

To all whom it may concern:

Be it known that I, Ernest H. Westmore, a British subject, residing at North Hollywood, in the county of Los Angeles and State of California, having invented a new, original, and ornamental Design for an Eyebrow Stencil, of which the following is a specification, reference being had to the accompanying drawings, forming a part thereof.

Fig. 1 is a perspective view of an eyebrow stencil, showing my new design; Fig. 2 is a top plan view of the eyebrow stencil; Fig. 3 is a side elevation of the eyebrow stencil taken from one side; Fig. 4 is a side elevation of the eyebrow stencil taken from the other side thereof; Fig. 5 is an end elevation of the eyebrow stencil taken from one end, and Fig. 6 is an end elevation of the eyebrow stencil taken from the other end thereof.

I claim:

The ornamental design for an eyebrow stencil, as shown.

ERNEST H. WESTMORE.
